UNITED STATES PATENT OFFICE.

ALBERT E. JOHNSON, OF BEVERLY, MASSACHUSETTS, ASSIGNOR TO UNITED SHOE MACHINERY COMPANY, OF PATERSON, NEW JERSEY, A CORPORATION OF NEW JERSEY.

LUBRICATING DEVICE FOR SEWING-MACHINE NEEDLES.

1,108,445.

Specification of Letters Patent.

Patented Aug. 25, 1914.

Application filed January 13, 1913. Serial No. 741,829.

To all whom it may concern:

Be it known that I, ALBERT E. JOHNSON, a citizen of the United States, residing at Beverly, in the county of Essex and State 5 of Massachusetts, have invented certain new and useful Improvements in Lubricating Devices for Sewing-Machine Needles; and I do hereby declare the following to be a full, clear, and exact description of the invention, such as will enable others skilled in the art to which it appertains to make and 10 use the same.

The present invention relates to needle lubricating devices for sewing and stitching machines which are used in the manufacture of boots and shoes, and more particularly to such devices for sewing machines used to sew together the two upturned lips of an "Economy" insole blank.

20 In operating these machines for sewing sole leather it is found that the needle breaks up the leather at the point of penetration into fine particles of dust which gather on the surface and in the eye of the needle. These 25 particles of dust ordinarily are too light and fine to restrict the passage of the thread through the eye of the needle, but as the needle is vibrated at a high speed it soon becomes heated to such an extent as to cause 30 the fine particles of dust to burn on the needle. The burned dust is exceedingly sticky and, instead of being easily displaced by the reciprocation of the needle, soon clogs up the eye of the needle thus causing the thread 35 to be caught therein and broken. It has been discovered that the danger of the thread becoming broken can be obviated by either dipping the thread in an oil bath or squirting oil on the needle. Neither of these 40 methods are, however, economical in the use of oil.

The object of the present invention is the provision of a needle lubricating device of simplified and improved construction and 45 mode of operation which will be economical and will work satisfactorily at a high speed without spattering the oil over the work in the machine.

To the accomplishment of this object the 50 features of the invention relate to certain devices, combinations and arrangements of parts, hereinafter described and then set forth in detail in the appended claims

which possess advantages readily apparent to those skilled in the art. 55

The various features of the present invention will be best understood from an inspection of the accompanying drawings, showing the best form of the invention at present known to the inventor, in which,

60 Figure 1 is a front elevation of a Willcox & Gibbs Household sewing machine, in which the novel features of the present invention have been embodied; Fig. 2 is a detail in left side elevation; Fig. 3 is a detail 65 in sectional plan on the line 3—3, Fig. 2, and Fig. 4 is a sectional detail on the line 4—4, Fig. 1.

65 The construction and mode of operation of the stitch forming mechanism of the machine shown in the drawings are substantially identical to the construction and mode of operation of the stitch forming mechanism provided in the well known Willcox & Gibbs Household sewing machine. This 70 stitch-forming mechanism comprises a straight, eye-pointed needle 1 and a rotary thread hook or cast-off 2. The thread hook is rotated by being mounted directly upon the driving shaft 3. The needle 1 is 75 clamped upon the lower end of a needle bar 4 which is reciprocated, in a needle bar guide 5 on the machine frame, by the oscillations of a pivotally mounted lever 6 actuated by an eccentric on the shaft 3. 85

In order to lubricate the needle 1 a plug 90 of absorbent material 7, such as felt, is mounted in a bore 8 formed in the lower end of a holder 9. The rear end of the bore 8 is open to permit a small quantity 95 of oil to be squirted therein, as may be necessary, which is retained by the felt plug 7 until it is applied to the needle. To enable the felt plug 7 to automatically accommodate itself to needles of different sizes and 100 to exert the required pressure upon the needle regardless of the reduction in size of the plug due to wear the holder 9 is pivotally mounted upon the needle bar guide 5 and is normally held under spring tension 105 in such manner as to project the felt plug 7 into the plane of the path of movement of the needle. To this end the holder 9 is provided intermediate its ends with a boss 10 which is rotatably held by a washer 11 110 secured to a bracket 13 which

is clamped to the back of the needle guide 5. In order to swing the holder 9 on the stud 12 in a direction to project the felt plug 7 into the plane of the path of movement of the needle a spring 14 is clamped to the end of the stud 12 by a screw bolt 15. One end of the spring is held in a hole 16 formed in the end of the stud 12 and the other end of the spring is arranged to 10 exert pressure against the left side (viewing Fig. 1) of the holder 8.

In order to permit the needle bar to descend below the felt plug 7 without engagement therewith the needle lubricating device 15 is arranged to be withdrawn from the needle in a plane transverse to the path of movement of the needle. To this end the upper end of the holder is provided with a cam surface 17 which is held by the spring 20 14 continuously in engagement with a roll 18 journaled upon a screw bolt 19 (Fig. 4) secured to a roll carrier 20. The roll carrier 20 is bifurcated to embrace the lever 6 to which it is clamped by a screw bolt 21.

25 With this construction the lubricating device is yieldingly held against the needle until, during the downward movement of the needle, the roll 18 engages an incline 22 on the cam surface 17 at which time the lubricating device is withdrawn from the needle to permit the passage of the needle bar below the lubricating device. As soon as the needle bar is elevated the roll 18 rides off the incline 22 thus permitting the spring 30 35 14 to replace the lubricating device against the needle.

The nature and scope of the present invention having been indicated and the preferred form of the invention having been 40 specifically described what is claimed as new, is:—

1. A sewing machine, having, in combination, a needle, a needle lubricating device, yielding means for holding the lubricating 45 device against the needle, and positive means acting in opposition to said yielding means for withdrawing the lubricating device from the needle by a movement in a path transverse to the path of movement of the needle.

2. A sewing machine, having, in combination, a straight needle, a needle bar, a needle lubricating device normally maintained in engagement with the needle, and a single 55 means for vibrating the needle bar and needle vertically and for withdrawing the needle lubricating device from the path of movement of the needle bar as it descends.

3. A sewing machine, having, in combination, a straight needle, a needle bar,

means for causing a reciprocation of the needle, an independently mounted needle lubricating device normally held in the path of movement of the needle, and means other than the needle bar, for positively withdrawing the needle lubricating device from said path. 65

4. A sewing machine, having, in combination, a needle, a needle carrier, a needle lubricating device, a holder therefor movable about a fixed axis, yielding means for swinging the holder in one direction about said axis to project the lubricating device into the path of movement of the needle, and positive means other than the needle 70 carrier, for swinging the holder in the other direction about said axis to withdraw the lubricating device from the path of movement of the needle. 75

5. A sewing machine, having, in combination, a needle, a needle carrier, a needle actuating lever, means for vibrating said lever, a needle lubricating device, a holder for said device mounted on a lever movable about a fixed axis, and means separate from 80 said means for vibrating the needle actuating lever and separate from the needle carrier for engaging said lubricating device lever to swing the holder about said axis and cause the lubricating device to move into 85 and out of the path of movement of the needle.

6. A sewing machine, having, in combination, a needle, an oscillating actuator therefor, a needle bar, a needle bar guide, 90 a needle lubricating device pivotally mounted on the needle bar guide, means for holding the needle lubricating device projected into the path of movement of the needle, and means carried by the oscillating actuator for removing the needle lubricating device from the path of movement of the needle. 100

7. A sewing machine, having, in combination, a needle, an oscillating actuator 105 therefor, a needle bar, a needle bar guide, an arm centrally pivoted on the needle bar guide and provided with a cam and a needle lubricating device, means for normally maintaining the needle lubricating device 110 projected into the path of movement of the needle, and a roll carried by the oscillating actuator arranged to engage the cam on the arm and remove the needle lubricating device from the path of movement of the 115 needle.

ALBERT E. JOHNSON.
